UNITED STATES PATENT OFFICE.

MASCHIL D. CONVERSE, OF NEWARK, NEW JERSEY, ASSIGNOR, BY MESNE ASSIGNMENTS, TO HOWE AND METALLIC CAP COMPANY, OF NEW YORK, N. Y., A CORPORATION OF NEW YORK, **CLOSURE FOR JARS, BOTTLES, AND LIKE RECEPTACLES.**

No. 888,696. **Specification of Letters Patent.** Patented May 26, 1908.

Application filed January 14, 1907, Serial No. 352,204. Renewed November 8, 1907. Serial No. 401,327.

To all whom it may concern:

Be it known that I, MASCHIL D. CONVERSE, a citizen of the United States, residing at Newark, in the county of Essex and 5 State of New Jersey, have invented certain new and useful Improvements in Closures for Jars, Bottles, and Like Receptacles, of which the following is a specification.

My present invention relates to metallic 10 closures for bottles, jars and other like receptacles, and particularly to that type composed of a cap adapted to inclose a disk of cork or other sealing medium, and a second part attached thereto, adapted to have its 15 lower edge turned under the annular shoulder of the neck of the receptacle to be sealed, while held by downward pressure in place upon the brim thereof.

The objects of my invention are to provide 20 an efficient and inexpensive closure of this type that may readily be removed from the receptacle, in unsealing the same, without the employment of any key or other implement, and by the form of construction of one 25 part (the cap) thereof, to incidentally provide against the separation therefrom or falling out of the disk of cork or other sealing medium, thus insuring greater efficiency 30 of the cap portion for use as a temporary cover or lid for the receptacle after its sealing.

To this end my present invention is comprised of a cap or shell, adapted to inclose a disk of suitable sealing material, provided 35 with equal spaced circumferentially aligned slits through the dependent flange, each having the upper marginal edge of the metal indented or turned slightly inward, in a horizontal plane just below the plane occupied by 40 the sealing disk; and of a further part, viz., an annular dependent ductile member secured circumferentially within said cap, and adapted to have its lower edge turned under the shoulder of the neck of a receptacle in 45 sealing of the latter, said member being formed from a straight strip of metal, and having the features which will hereinafter be fully shown.

In the drawings: Figure 1, partly sec- 50 tional, is a side elevation of my improved closure complete and in place upon a jar. Fig. 2, partly sectional, is a side elevation of the same, illustrating the construction and manner of assembling before application to a 55 receptacle. Fig. 3 is a straight strip of duc-

tile metal in one margin of which are equally spaced slits, showing the manner of making the holding member of the closure. Fig. 4 is an interior view of the cap part only, with the sealing medium and holding member 60 removed. Fig. 5 illustrates my invention complete before insertion of the sealing disk, and before application to a receptacle, all of which will be hereinafter described in detail.

Like letters indicated corresponding parts 65 throughout the several figures.

A, is the cap portion, the continuous circumferential dependent flange of which is provided with a plurality of horizontally aligned equal spaced slits, a, a, a, the upper 70 edges of which are bent slightly inward. Within this cap a disk of cork, D, or other suitable sealing medium, is placed.

B, is the dependent ductile metal holding member, made of a straight piece of sheet 75 metal, and having one margin thereof cut at equally spaced intervals (corresponding by measure to the widths of the slits (a) in the cap and the spaces separating the same), so that when the two ends thereof are bent 80 around to abut each other, and the flat ring so formed is inserted within the cap, every alternate section, b, b, b, thereof, commencing with the half sections b¹, b², at the respective ends, may be pushed upward and slipped 85 by slight outward curvature through the corresponding lateral slits, a, a, a, in the flange of the cap, (see Fig. 2) until the upper edge of each of the intervening sections is seated against the interior of the top of the 90 cap, as shown at e, when the protruding ends, by being bent downward, as at b, b, in Fig. 5, will securely fasten the cap, A, and this holding member, B, together. The sealing me- 95 dium, D (seen in Fig. 1), may now be forced into the position required above the horizontal plane of in-turned edges of the slits, a, a, a, which will effectually prevent its falling out.

My invention constructed and assembled 100 as shown and described, may now be applied to receptacles in the way and by the means hereinbefore mentioned, and will then appear as represented in Fig. 1.

To unseal a receptacle sealed with my pres- 105 ent invention, the turned down ends, b, b, b, (see Fig. 5) are, by the thumb or finger nail (or otherwise, if preferred) turned upward to the positions shown in Fig. 2 (which, by rea- 110 son of the ductility of the metal, is easily ac-

complished), thus unlocking the cap, A, which may now be readily removed. The part, B, can now be discarded, and the cap, A, with the sealing medium still held in place by the in-turned edges of the slits, a, a, a, used as a lid or cover for the receptacle.

Those skilled in the art will readily see that my present improved closure may be manufactured at small cost.

10 Having described my invention, what I claim as new and desire to secure by Letters Patent, is:

15 In a metallic closure of the class described, in combination, a cap, adapted to inclose a sealing medium, having its circumferential dependent flange pierced in substantial hori-

zontal alinement by equal spaced slits with in-turned upper margins, an annular, ductile holding strip, bent to form a flat ring, adapted to have its lower edge turned under the shoulder of a receptacle, and alternate correspondingly spaced marginal securing sections (b) integral of said strip entered through said lateral circumferential slits from within, and bent downward exteriorly of, the cap. 20 25

In testimony whereof I have signed my name to this specification in the presence of two subscribing witnesses.

MASCHIL D. CONVERSE.
